Primary Examiner — Barbara Fox*Assistant Examiner* — Mehri F Bajoul(74) *Attorney, Agent, or Firm* — Hovey Williams LLP(57) **CLAIM**

The ornamental design for a pet toy, as shown and described.

DESCRIPTION

FIG. 1 is a top right perspective view of a pet toy embodying my design;

FIG. 2 is a top left perspective view of the pet toy of FIG. 1;

FIG. 3 is a front elevational view of the pet toy of FIG. 1;

FIG. 4 is a rear elevational view of the pet toy of FIG. 1;

FIG. 5 is a left end view of the pet toy of FIG. 1;

FIG. 6 is a right end view of the pet toy of FIG. 1;

FIG. 7 is a top plan view of the pet toy of FIG. 1; and,

FIG. 8 is a bottom plan view of the pet toy of FIG. 1.

The broken lines shown in the drawings depict portions of the pet toy that form no part of the claimed design.

1 Claim, 4 Drawing Sheets(56)
